BEDSTEAD

Ernest Herrmann, Westport, Conn., assignor to Heywood-Wakefield Company, Gardner, Mass., a corporation of Massachusetts

Application August 8, 1958, Serial No. 52,125

Term of patent 7 years

(Cl. D5—4)

Fig. 1.

Fig. 2.

Fig. 3.

Fig. 4.

Fig. 1 is a perspective view of a bedstead showing my new design;

Fig. 2 is a front elevation of an end member for a bed showing my new design but on a scale larger than that of Fig. 1;

Fig. 3 is a vertical sectional view on the line 3—3 of Fig. 2; and

Fig. 4 is a fragmentary horizontal sectional view on the line 4—4 of Fig. 2, but on a larger scale.

The dominant features of my design are shown in full lines on the drawing.

I claim:

The ornamental design for a bedstead, substantially as shown and described.
